LOOSENING APPARATUS FOR WALL
COVERINGS

Albert S. Christopher, Chicago, Ill.

Application September 28, 1949, Serial No. 118,377

7 Claims. (Cl. 126—271.1)

1

This invention relates in general to loosening apparatus for wall coverings and more particularly to apparatus for loosening old wall paper and similar wall coverings or coatings to facilitate the removal thereof from walls or like surfaces.

An important object of the invention is to provide such apparatus which will be quick in starting and in operation. In similar apparatus provided heretofore, steam is supplied from a remote source such as a boiler wherein a considerable quantity of water is heated to provide the steam. The time lag in such an operation is proportional to the volume of water in the boiler and is, therefore, ordinarily considerable. In accordance with my invention, this time lag is materially reduced or substantially eliminated by generating steam at the applicator where a small volume of water may be rapidly heated to provide the steam and this under the constant control of an operator as operating conditions may require.

Another object is to provide for conditioning steam at the applicator, such as by introducing water or mixing water therewith to increase the moisture content thereof in accordance with surface requirements. Relatively dry steam is required for the loosening of surface coverings having paint, varnish or similarly impervious exterior coatings thereon while relatively porous surface coverings such as wall paper and some hardened plaster coverings may be more readily loosened for removal by the application thereto of saturated or wet steam. Apparatus constructed in accordance with my invention permits ready adjustment by an operator so that either dry or wet steam may be applied to surfaces in accordance with requirements without materially interrupting operation of the applicator.

Other objects, and structural features, will be obvious as the invention is better understood from the following description, which, taken in connection with the accompanying drawings, discloses an embodiment thereof.

Referring to the drawings,

Fig. 1 is a diagrammatic view illustrating apparatus embodying the invention including an applicator;

Fig. 2 is a plan view showing the top of the applicator illustrated in Fig. 1;

Fig. 3 is a side elevational view of the same, viewing the applicator from the left in Fig. 1;

Fig. 4 is a sectional view taken substantially on line 4—4 in Fig. 3 showing one side of the applicator with certain parts broken away to show details of construction;

Fig. 5 is a detail section taken substantially on line 5—5 in Fig. 4 showing one of the steam jets and other structural details; and

2

Fig. 6 is a diagrammatic sectional view showing enlarged structural details for mounting an adapter as intercepted on the plane 6—6 in Fig. 1.

The features of my invention include the provision of apparatus for applying relatively dry steam directly to wall surfaces when required and similarly apparatus for applying wet steam to such surfaces when the condition of the surface requires or permits. These features may be incorporated in varying form in accordance with predetermined requirement, such as where limited operation is required a relatively simple or mostly self-contained unit may be utilized, while extensive or long continued operational requirements may be most efficiently expedited by such apparatus in which the applicator is arranged for connection to one or more remotely located supply sources so that periodic recharging operations would not be required. To illustrate one such embodiment arranged for receiving fuel and water supplies from remote supply units, I have shown a water tank 11, having a power operable pump 12 associated therewith, a high pressure fuel tank 13, an applicator unit 14, and flexible conduits 15 and 16 connecting the applicator unit 14 with the pump 12 and the fuel tank 13 respectively.

The water supply tank 11 may be any suitable container such as the open tank shown, to which the pump 12 may be operably connected for supplying water under pressure to the applicator unit 14 through the conduit 15. A suitable by-pass pressure regulator 21 may be connected in the pump discharge pipe 22 to which the conduit 15 is connected. Obviously the conduit 15 may be connected directly to a suitable water supply when such is available, or a small water container may be mounted directly on the applicator when water requirements are not extensive.

The fuel tank 13 illustrated is a commercial high pressure container in which any suitable fuel gas may be stored under relatively high pressure, having a pressure regulator 23 controlling the outlet thereof whereby the gas pressure may be reduced in accordance with requirements before being discharged into the conduit 16 whereby it is conducted to the applicator 14. A suitable pressure gage 24 may be connected with the conduit 16 to indicate operating pressure.

The applicator 14 is essentially a pan shaped hood 31, a peripheral laterally extending flange 32 of which defines a suitable steam chamber when placed against a wall surface, a suitable manipulating handle 33 whereby the hood 31 may be moved over or pressed against a wall surface, and at least one jet or nozzle 34 through which steam may be discharged under the hood 31 or into the steam chamber formed thereby.

In the present embodiment two steam generators 35 are carried by the hood 31 and a gas

burner 36 is provided for each one of the steam generators 35. These units are provided in duplicate for balance and high operating efficiency, but it will be obvious that the applicator may be provided with more or less of such units upon occasion as above indicated. All duplicate parts in these units are identified by the same reference numerals.

The steam generator 35 illustrated includes a series of helical windings or coils of relatively small diameter metallic tubing, such as an inner coil 41 and an outer coil 42. These coils are preferably formed of a continuous tube which is provided with suitable fittings at each end thereof, whereby it may be connected to a control valve 43 and a mixing head 44. The coils 41 and 42 are preferably close wound and are proportioned and arranged to form a duct 45 at the upper end of the coil 41. Where the coils are not in lapped relationship, the exterior surfaces thereof may be covered with an insulating sleeve such as the sleeves 46 and 47 and a metal sleeve 48 mounted over the sleeve 47 and carrying a closure plug 49 of insulating material forms a heat trap 51 at the top of the coils.

The steam generator 35 is carried on the applicator 14 through its connections with the valve 43 and the mixing head 44. The valve 43 is rigidly mounted on a supply pipe 52, as shown in Fig. 4, and the mixing head 44 is rigidly mounted in the hood 31 by means of the nozzle 34 as shown in Fig. 5.

The supply pipe 52 is arranged for connection to the conduit 15 and is branched out for connection to the valves 43. A continued extension 55 of the pipe 52 connects to a control valve 56 whereby water may be supplied to the mixing head 44 through a balancing valve 57 connected to the control valve 56 by a pipe nipple 58 and to the mixing head 44 by a nipple 59.

A stem 62 of the control valve 56 extends through a bracket 63 of the handle 33 for engagement by a pivoted lever 64 having pivotal support on the bracket 63 as at 65, Fig. 5, and extending therefrom for engagement by an operator. The valve 56 may be of a type in which the line pressure tends to unseat the valve and this tendency may be normally counteracted by a suitable compression spring 66. A threaded screw 67 extending through the lever 64 and having threaded engagement in the bracket 63 locates the spring 66 and provides means for regulating the valve 56.

The extension 55 of the supply pipe 52 extends through an opening 68 in a lower bracket 69 of the handle 33 for support therein.

The gas burners 36 include a jet 71 arranged to discharge fuel into a combustion tube 72 carried in a bracket 73 which is attached to the hood 31 with the jet 71 and tube 72 arranged to heat the steam generator 35. The jet 71 is connected through a control valve 74 to a supply pipe 75 which is arranged for connection to the conduit 16. It will be obvious that any suitable commercial heating unit operating on gaseous or liquid fuels or by electricity such as may be controlled by an operator may be utilized for generating steam as above described.

While the applicator hood 31 illustrated is rectangular or substantially square in outline to facilitate operation into square corners, it will be obvious that hoods of other shapes can be provided when required by operating conditions such as when relative narrow recessed surfaces

are to be treated an elongated rectangular hood may be provided, and where curved surfaces may be encountered correspondingly curved hoods may be provided.

To provide means for adapting the applicator shown to abnormal surfaces, I have shown an adapter 81 of oblong or elongated rectangular form and relatively deep to facilitate operation in relatively deep recesses. The adapter 81 and hood 31 are arranged for detachable mounting of the adapter 81 to permit independent operation of the hood 31 or substitution of the adapter for other interchangeable adapters formed in accordance with other surface conditions as above described.

The adapter 81 may be formed of any suitable material, such as sheet metals, arranged to form a hollow tube of rectangular or other suitable form having a laterally extending base flange 82 formed at one end thereof. A sponge rubber or similar gasket 83 may be clamped between the adapter flange 82 and the hood 31 for sealing the joint. The base flange 82 is proportioned to fit freely inside of the peripheral flange 32 of the hood 31 at two points on opposite edges of the hood 31, Figs. 1, 2 and 6, so that when the flange 82 is engaged behind a retaining flange 84 extending laterally from the peripheral flange 32, an opposite edge portion of the flange 82 may be clamped against the gasket 83 and the hood 31 by means of a suitable clamping device to rigidly mount the adapter on the hood 31 in sealed relationship therewith. Retaining flanges 84 may be provided on two edges of the hood 31 as shown to facilitate attachment of the adapter 81 in either vertical or horizontal relationship.

A suitable latching device is illustrated in Figs. 1, 2 and 6, including a hook element 85 and a latch bar 86. The hook element having a hinged connection with the latch bar at a point 87 near an end 88 thereof. The end 88 is formed out of alignment with a plane extending between the point of the hook 85 and the bearing point 87 so that it will normally remain in latching position as shown until the remote end of the bar 86 is lifted or rotated counter-clockwise. To clamp the adapter to the hood for operation the hook 85 and end 88 are engaged with the hood and flange 82 respectively and draw these parts together in clamped relationship as an incident to clockwise rotation of the bar 86.

In operation, water and fuel is supplied under pressure through the conduits 15 and 16 to the applicator 14 when same is operably connected thereto. To start steam generation one or more of the gas burners 36 may be started and adjusted by means of control valve 74 to preheat the coils 41 and 42. Heat from the burner circulates upwardly through the coil 41 into the heat trap 51 and then downwardly between the coils as indicated by arrows in Fig. 4.

The applicator is then ready for operation and by adjustment of the valve 43 relatively dry steam will be generated and issue from the nozzle 34 in such volume as may be determined by the adjustment of the valve 43. Pressure may be built up under the hood 31 or in the adapter 81 by pressing the applicator against the surface under treatment to restrict the escape of steam.

When a relatively wet steam is required by the surface under treatment, water may be mixed with the dry steam to condition the steam in accordance with requirements. This may be accomplished by depressing the lever 64 and thereby opening the water control valve 56 to

the extent required by surface conditions. The balancing valve 57 is provided to facilitate balancing by means of an adjusting screw 91 to equalize the flow of water when two or more steam generating units are coupled for simultaneous operation.

Pressure on the lever 64 releases water into the mixing head 44 where it is mixed with steam in a mixing chamber 92 and as an incident to its discharge through the nozzle orifice 93, Fig. 5. Upon occasion the operating position of the lever 64 may be fixed by the adjusting screw 67 so that constant pressure on the lever 64 by an operator need not be required.

A suitable heat guard 95, such as a formed sheet metal covering, may be attached to the handle 33 and to the hood 31 to shield an operator's hand from excessive heat during operation.

It is thought that the invention and many of its attendant advantages will be understood from the foregoing description, and it will be apparent that various changes may be made in the form, construction, and arrangement of the parts without departing from the spirit and scope of the invention, or sacrificing all of its material advantages, the forms herein-before described being merely preferred embodiments thereof.

I claim:

1. An applicator adapted for manipulation over a wall surface to effect the loosening of wall paper or similar coating thereon, comprising a body having a handle and a steam confining hood for confining steam to predetermined surface areas, means including a continuously operable steam generator and a conductor for discharging steam under the confining hood, and periodically operable means including a separate conductor for discharging water into the steam conductor adjacent the confining hood for mixture with the steam prior to the discharge thereof under the confining hood so that the moisture condition of the steam may be instantaneously controlled in accordance with operating requirements.

2. An applicator for manipulation over a wall surface to effect the loosening of wall paper or similar coatings thereon, comprising a body having a handle and a steam confining hood wherein steam may be confined and applied to a wall surface, said body carrying steam generating means connected with the confining hood and arranged for control by an operator, and water mixing means carried by said body and connected with the steam generating means near the connection thereof with the confining hood, said water mixing means including a manually operable flow control valve arranged for manipulation by an operator by means of which steam may be instantaneously conditioned by addition of water for application in accordance with varying surface conditions.

3. A steam generating applicator including a hood shaped body adapted for manipulation over wall surfaces for the purpose of effecting the loosening of wall paper or similar coatings thereon, said applicator carrying continuously operable steam generating means, having a fixed outlet in the hood shaped body, and manually controlled variable water injecting means also carried by said body and connected with the steam generating means adjacent the fixed outlet thereof and being operable for instantaneously mixing water with steam from the steam generating means.

4. An applicator for manipulation over a wall

surface to effect the loosening of wall paper or similar coatings thereon, comprising a body having a handle and a hood for confining steam to predetermined surface areas, steam generating means carried by said body having connections for receiving water supplies from a remotely located source and a mixing head having a discharge outlet for discharging steam under the hood, and means including a by-pass connection and a control valve operably connected with the mixing head for directly injecting water into the steam at the mixing head for mixture with the steam adjacent the discharge outlet therein.

5. In an applicator for the purpose described the combination of a body having a recessed side for cooperation with a wall surface to form a steam chamber, means including a connecting head and a conduit connected therewith for conducting a constant supply of steam to the recessed side of the applicator, said connecting head having a discharge opening into the steam chamber, with manually operable steam conditioning means connected therewith at the connecting head for injecting water therein for mixture with the steam prior to the discharge thereof through the discharge opening.

6. In an applicator for the purpose described the combination of a body having a recessed side for cooperation with a wall surface to form a steam chamber, continuously operable steam generating means carried by said body for supplying steam continuously, and means including a mixing head and a conduit connecting the steam generating means with the steam chamber and having a discharge opening therein, with steam conditioning means for saturating steam by the injection of water, said conditioning means being attached to the mixing head and including a manually operable variable flow control valve.

7. An applicator adapted for manipulation over a wall surface to effect the loosening of wall paper or similar coating thereon, comprising a body having a handle and a steam confining hood for confining steam to predetermined surface areas, steam generating means carried by said body and having water supply line connections for receiving water supply from a remotely located supply source, said steam generating means being operably connected to a discharge head for discharging steam under the confining hood, and means including a by-pass conduit and an interconnected control valve therefor mounted for control by an operator for passing water from the water supply line connections into the discharge head for mixture with steam therein.
